UNITED STATES PATENT OFFICE

2,603,761

CATHODE-RAY TUBE

Walter E. Angell, Brooklyn, N. Y.

Application May 2, 1951, Serial No. 224,097

2 Claims. (Cl. 315—3)

1

This invention relates to electron beam or cathode ray tubes, such as used for oscilloscopes, television tubes or the like and it has for its primary object to provide an electron beam or cathode ray tube which has a longer lifetime and is less subject to destruction by accident than tubes of the standard construction.

A beam electrode or cathode ray tubes are rather expensive units and their lifetime is largely governed by the lifetime of the heated filament of the cathode which is also the most sensitive part of the tube on account of the high temperatures to which it is subjected and on account of the slow disintegration which is connected with the temperature and with the operational conditions of the tube.

According to the invention the cathode ray tube is provided with two cathode filaments which may be used alternatively for producing the electron emission of the tube and the change over from one cathode filament to the other is produced by a switch built into the socket of the tube in such a manner that neither the switch nor the handle of the same protrudes to a marked extent, thus permitting to insert the tube into any socket and into any assembly between parts so spaced and arranged that they will accommodate a conventional tube of the same type and size. While attention may be paid to locate the switch preferably at a point which is usually accessible and not obstructed by other parts of the set, it is not imperative to make special provisions, as the tube may be removed, if need be, for the switching operating and may afterwards be replaced.

The principal object of the invention is therefore to provide an electron beam or cathode ray tube with more than one filament and with means for switching in a filament kept in reserve as soon as the filament originally used is destroyed or has disintegrated or is thought to be less effective than expected.

A further object of the invention consists in arranging the switching means in such a manner that they are completely contained within the socket of the tube with practically no part projecting or protruding from the socket and with practically no change in the appearance or in the outline of the socket.

A further object of the invention consists in keeping the socket substantially closed after the lamp has been fixed within the socket so as to exclude the intrusion of extraneous objects or particles, even of small particles, such as dust or other particles floating in the air after the tube has been fixed to the socket.

2

Further objects of the invention will be apparent from the following detailed specification.

The invention is illustrated in the accompanying drawing by way of example only. Only one embodiment of the invention is shown in the accompanying drawing, but it is to be understood that the embodiment shown was selected for the purpose of explaining the principle of the invention and the best mode of applying said principle. No survey of the possible embodiments of the invention is given in the specification and a departure from the example shown in the drawing is therefore not necessarily a departure from the principle of the invention.

15 15 In the drawing:

Figure 1 is an elevational view of the lower portion of a cathode ray tube.

Figure 2 is a sectional elevational fractional view through the lower part of a cathode ray tube on an enlarged scale.

Figure 3 is a perspective view of the slide used in connection with the invention.

Figure 4 is a diagram of the connections.

The cathode ray or electron beam tube 10 as shown in Figure 1, is provided with the conventional cylindrical hollow socket 11, usually made of plastic material, having an upper inwardly bent annular flange 17 through which the lower end 18 of the tube projects and on which it is fixed. The bottom portion 12 of said socket carries the base pins 15, 16 of which only two are shown. The tube 10 is shown as being provided with two filaments 18, 20 joined by a conductor 19 to each other while each filament is moreover in addition provided with a separate connection 21, 22, respectively, each leading to a contact 24, 25, respectively.

These contacts are preferably buttons formed by the head of screw bolts (not shown) screwed into threaded holes of the sockets and the said heads may rest upon a washer or contact plate 26. The two contacts 24, 25 are suitably spaced and are arranged in the interior of the socket so that the wires 21, 22 leading from the filaments may be easily fixed and soldered to them.

40 40 Above these two contacts 24, 25 the socket 11 is provided with a narrow slot 30 leading from the interior of the socket into a recess 31 provided on the outside of the socket. This recess is preferably cross-shaped with an elongated middle section 35 and with much narrower upper and lower extensions 33. The portions of the socket which are adjacent to the said middle portion 35 and to the extensions 33 are preferably provided with undercuts 34 adjoining to the middle portion of the recess and reaching

from the extensions to the ends of said middle portion. A slide 36 which may also be cross-shaped may be placed into the recess 31. The middle portion 38 of the slide may have approximately the thickness of the recess 31 or a thickness slightly in excess of the same and the outer surface of the slide may be roughened or slightly corrugated to facilitate manipulation of the slide. The two upwardly and downwardly projecting wind portions 39 of the slide are of a reduced thickness corresponding to the width of the undercuts 34 and their length is preferably substantially equal to the width of the upper and lower extensions 33 of the recess 31.

The slide may be made of a material identical with that of the socket, which is usually pressed from molded plastic material, and carries on its backside a contact spring in the shape of an elastic tongue 40 which may have a tip embedded and firmly anchored within the plastic material of the slide 36. The contact spring or tongue 40 passes through the slot 30 in the socket and the tip of the tongue may be provided with a depression or with a hole and may engage one of the contact buttons 24, 25. To this contact spring or tongue 40 the end of a wire 42 is soldered, the other end of which is attached and soldered to one of the base pins 15. The wire must be long enough and must be so bent or coiled that a limited movement of the slide is permitted without putting a strain on the soldered end connections.

The resilient tongue or contact spring 40 moves with the slide and in the two end positions of the same makes contact with the two contact buttons 24, 25. The depression or hole serves to produce fixation of the tongue and of the slide in such an end position without preventing movement of the slide if some lateral force is applied to the corrugated outer surface of the slide portion which is approximately flush with the outer surface of the socket.

The slide may be fitted into the recess 31 by threading the tongue 40 through the slot 30 while the slide is in the center of the recess and the wings 39 of the slide fit exactly over the cuts or extensions 33 thus permitting the slide to enter into the recess 31 completely with the outer surface of the slide 36 flush with the socket. When this position has been reached the slide may be displaced laterally to the right or to the left and during such displacement the wings 39 of the slide will enter the undercuts 34 and the slide will be guided during its movement by the said undercuts and will be held in its place. When moved to one end of the recess the tongue 40 engages one of the contacts buttons 24 or 25 according to the position of the slide. As seen from Figure 4, if one of the base pins 16 is connected with the wire 19 joining the two filaments 18 and 20 the movement of the contact spring 40 on the slide and its contact with one of the two buttons 24 and 25 will determine which filament is connected with the source of current. If the filament has to be changed, pressure is applied on the outer side of the slide 36 and the latter is merely moved to the other side of the slot where it engages the other contact.

From the above it will be seen that the invention provides a cathode ray tube with a mul-

5 tiple filament, the individual filaments being switched in or out as desired by the operator of the tube, while at the same time the outline and appearance of the socket and the general construction remains unchanged. The user of the cathode ray tube may therefore, by substituting one filament for the other when burned out or broken, obtain a longer lifetime for the rather expensive tube than this was possible with the tubes as now used while no special provision need be made to accommodate the tube according to the invention.

10 It will also be understood that changes of unessential nature may be made without departing from the essence of the invention as defined by the annexed claims.

Having described the invention, what is claimed as new is:

15 1. A cathode ray tube, comprising a cathode member including a plurality of heated alternatively active filaments, a cylindrical socket surrounding the base of the cathode ray tube and having an enclosed bottom portion and an annular flange into which the base of the said cathode ray tube is inserted and in which it is firmly seated, thus providing a substantially closed space between said cathode ray tube and said socket, base pins projecting from the bottom portion of said socket, two of the base pins 20 being connectible with the cathode filaments, said socket being provided in its cylindrical portion with a recess on the outside and with a slot leading from the recess to the interior of the socket, a slide member adapted to move within said 25 recess, a switching member projecting from said slide member through the slot in the socket into the interior of the same, a plurality of fixed contacts on the inner surface of the cylindrical socket, positioned so as to come into operative 30 contact with the switch member upon movement of the slide in the recess, and connections leading from each of said filaments to said contacts, said switch member being connected to one of the base pins in order to produce alternatively a contact between one of said base pins and one of 35 said heated filaments.

40 2. A cathode ray tube as claimed in claim 1 in which the recess in the outer surface of the socket is cross-shaped and the slide member is substantially of the thickness of the recess, and in which the socket is further provided with undercuts adjacent to the cross-shaped recess, for guiding the slide member, while part of the surface of the slide member is exposed for manipulation without substantially protruding beyond the cylindrical surface of the socket.
